UNITED STATES PATENT OFFICE

160,851

CHAIN SAW

William L. Gillespie, Seattle, Wash.

Application September 28, 1949, Serial No. 5,203

Term of patent 14 years

(Cl. D93—3)

To all whom it may concern:

Be it known that I, William L. Gillespie, a citizen of the United States, residing at Seattle, in the county of King and State of Washington, have invented a new, original, and ornamental Design for a Chain Saw, of which the following is a specification, reference being had to the accompanying drawing, forming part thereof:

Fig. 1 is a perspective view of a chain saw embodying my new design, looking at the forward portion of the engine housing.

Fig. 2 is a perspective view of the chain saw looking at the rearward portion of the engine housing.

Figure 3 is a side elevation of the saw.

Figure 4 is a side elevation of the saw showing the reverse side of the view shown in Figure 3.

I claim:

The ornamental design for a chain saw, as shown.

WILLIAM L. GILLESPIE.
